UNITED STATES PATENT OFFICE.

HARRY A. MILLER, OF LOS ANGELES, CALIFORNIA.

SPARKING DEVICE.

No. 813,104.

Specification of Letters Patent.

Patented Feb. 20, 1906.

Application filed January 14, 1905. Serial No. 241,004.

To all whom it may concern:

Be it known that I, HARRY A. MILLER, a citizen of the United States, residing at Los Angeles, in the county of Los Angeles and 5 State of California, have invented a new and useful Sparking Device, of which the following is a specification.

My invention relates particularly to sparking devices for engines; and my primary object is to provide a reliable device of this character of simple and inexpensive construction.

In this construction internal contact members are employed, one of which contact members is operated by gas-pressure in one direction and by spring-pressure in the opposite direction, and in this construction secondary circuits and electromagnets with their attendant disadvantages are dispensed with.

My invention is illustrated in the accompanying drawings, in which—

Figure 1 is a sectional view of an engine-cylinder and my improved ignition device applied thereto, and Fig. 2 a broken side elevational view of the ignition device.

In the construction shown, A represents an engine-cylinder, and B my ignition device applied thereto. The device B comprises a plug b, having screw connection with the cylinder; a spring-held reciprocable contact member or plunger b', movable in a tubular member b², contained in an insulating-tube b³, extending vertically through the plug; a contact member b⁴ in the form of a lever, located 35 principally in the chamber b⁵ and supported on a pivot b⁶, the lower end of the lever being curved upwardly and tipped with a platinum point adapted to make contact with the platinum point at the lower of inner extremity 40 of the contact member b'; a diaphragm x, joined by a rod b⁷ to the upper end of the lever b⁴, an enlargement b⁸ affording a chamber b⁹, communicating through a passage b¹⁰ with the chamber b⁵; a removable plate b¹¹, 45 with which the diaphragm is connected and which affords one wall for the chamber b⁹, a spring b¹² serving normally to hold the diaphragm pressed inwardly, and an adjustable screw b¹³ connected with the enlargement on 50 the plate b¹¹ and recessed to receive the spring b¹², said screw serving as a means for adjusting the tension of said spring.

The contact member b' has an upwardly-extending reduced stem b¹⁴, which works in a

socket b¹⁵ of a binding-screw b¹⁶, and there is 55 provided a spring b¹⁷, tending to hold the member b' normally depressed.

A battery C is connected by a conductor c with the binding-post b¹⁸ and with the engine-cylinder. In the course of the conductor c is located a make-and-break device c', comprising a cam c², operated from the shaft of the engine, and a contact member c³. If desired, the external make-and-break device c' may be omitted from the external circuit. 65

The operation will be readily understood. The diaphragm x is normally pressed inward, as indicated in Fig. 1; and the internal contact members b' and b⁴ are out of contact. The tension of the spring b¹² is preparatorily 70 adjusted, so that when the pressure in the engine-cylinder (during compression of the charge) reaches the proper amount the diaphragm will be forced outward, thereby causing the inner end of the contact member b⁴ to 75 move with a wiping contact past the inner end of the contact member b'. When the internal pressure is relieved, the diaphragm will be returned to its normal position under the action of the spring b¹². Assuming the external make-and-break device c' to be in use, the external portion of the circuit will be closed at the proper instant to permit current to pass to supply the spark internally at the exact moment required. Assuming the 80 device c' to be dispensed with, sparking will occur at the exact moment desired, provided the spring b¹² has been preparatorily delicately adjusted to insure movement of the diaphragm at exactly the proper instant. It 85 will be understood, therefore, that the device c acts as a safety device, insuring passage of current at proper intervals only, and that where the engine operates under conditions where proper adjustment of the spring b¹² is 90 assured the device c' is unnecessary.

It is obvious that the present invention dispenses with secondary circuits and also with electromagnets with their attendant disadvantages.

Changes in details of construction within the spirit of my invention are feasible. Hence no undue limitation should be understood from the foregoing detailed description. While it is preferred to actuate the contact member b⁴ wholly by gas-pressure in one direction and by spring-pressure in the opposite direction, still the construction may be va-

ried in this respect, the gas-pressure being utilized in the actuation of the movable contact member in a partial degree only, if desired.

What I regard as new, and desire to secure by Letters Patent, is—

1. An ignition device, comprising a plug, a spring-held reciprocable contact member, an oscillating contact member, a chamber communicating with the inner end of the plug, and a member contained in said chamber and exposed to the cylinder-pressure and serving to actuate said second-named contact member, for the purpose set forth. 40
2. An ignition device comprising a plug, an insulating-sleeve extending therethrough, a contact member extending longitudinally through said sleeve, an oscillating lever-form contact member, and a diaphragm located so as to be exposed to cylinder-pressure when in use and serving to actuate said second-named contact member, for the purpose set forth. 45
3. An ignition device comprising a plug, a contact member having insulated connection with said plug, an oscillating contact member, a diaphragm connected therewith and normally in position to hold said contact members out of engagement, a spring bearing against said diaphragm, and means for adjusting the tension of said spring, for the purpose set forth. 50
4. The combination with an engine-cylinder, of an ignition device comprising two internal relatively movable contact members, 55

a diaphragm connected with one of said contact members, said contact members being normally separated, an electric circuit which may be completed through said contact members, and a normally open external make-and-break device interposed in said circuit, for the purpose set forth. 60

5. An ignition device, comprising a plug, an internal contact member connected therewith, a pivoted contact member, a diaphragm disposed at one side of said second-named contact member and connected with the same and exposed to pressure from the cylinder of the engine, and an adjustable spring bearing against said diaphragm, for the purpose set forth. 65

6. An ignition device, comprising a plug having a bore, an insulating-tube extending therethrough, a tube within said insulating-tube, a reciprocable contact member within said last-named tube, a chamber in said plug, a contact member pivoted in said chamber, a diaphragm disposed at one side of said last-named contact member and connected with said last-named contact member, a spring bearing on said diaphragm, means for adjusting said spring, and means for connecting the conductor of an electric circuit with said second-named tube, for the purpose set forth. 70

HARRY A. MILLER.
